INSIDE CASING CUTTER

George W. Bowen, Houston, Tex., assignor to
 S. R. Bowen Co., Huntington Beach, Calif., a
 corporation of California

Application August 26, 1936, Serial No. 97,911

12 Claims. (Cl. 164—0.4)

This invention relates to devices for cutting off pipes within wells and more particularly to what are known as inside pipe cutters or casing cutters in which the tool is lowered on a drill pipe down the well and into the pipe to be cut and there actuated to sever the pipe in response to predetermined actuating movements of the drill pipe from the surface.

An object of the invention is to provide an inside casing cutter particularly adapted to enter and sever a pipe the upper end of which is located a substantial distance below the upper end of the well, and to give an indication at the surface when the upper end of the pipe is reached and entered.

Another object of the invention is to provide a cutter which may be lowered into a pipe to be cut, actuated to sever the pipe, and then be automatically rendered inoperative in response to an upward pull whereby the tool may be subsequently raised, lowered or turned without again actuating the cutter.

Another object of the invention is to provide a positive and fool-proof releasing mechanism for release of the cutters when the level in the well is reached at which the pipe is to be severed.

Another object is to provide a simple and effective mounting for the knives or cutters in an inside pipe cutting tool and to provide an effective spring mechanism for normally retracting the knives.

Another object is to provide a construction in which the anchoring slips may be actuated to anchor the device at a desired point in the pipe by merely lowering the device on a drill string to the desired level and then rotating the drill string in one direction while maintaining it at a constant height.

Various other objects and specific features of the invention will become apparent from the detailed description which follows and it is to be understood that the scope of the invention is to be limited only in accordance with the claims.

Referring to the drawings:

Fig. 1 is a vertical elevation view showing an inside pipe cutter in accordance with the invention position within a pipe, the latter being shown in section;

Fig. 2 is a detailed view partly in section showing the upper portion of the cutter structure which is disclosed in full in Fig. 1;

Fig. 3 is a detailed view partly in section showing the lower end of the mechanism; and

Figs. 4, 5, 6, 7, 8, 9, 10 and 11 are section views taken in the planes IV—IV, V—V, VI—VI, VII—

VII, VIII—VIII, IX—IX, X—X, and XI—XI, respectively, of Fig. 2.

Referring first to Fig. 1, there is shown a pipe 1 within which is mounted a cutter in accordance with the invention shown suspended on the lower end of a string of drill pipe 2. Thus the lower end of the drill pipe 2 (referring to Fig. 2) is threaded into the upper end of a coupling member 3 which in turn is connected by tapered screw threads 4 to the upper end of an upper arbor 5. This upper arbor 5 extends downwardly for a substantial distance and is connected at its lower end by threads 6 to the upper end of a lower arbor 7, the latter extending clear to the lower extremity of the device where it terminates in a guide cap 8, the latter being threaded onto the lower end of the lower arbor and secured in place by a set screw 9. The arbors 5 and 7 function as a single unit in operation of the device and are made in two sections only for convenience in manufacture and assembly.

Adjacent its upper end the upper arbor 5 is enlarged so that its outer surface is substantially cylindrical and flush with the outer surface of the lower portion of the coupling 3 and is provided with vertical radially extending slots 11 in which are mounted knives 12. Each knife 12 is dimensioned to fit freely within its slot and is provided with a circumferentially expanded head 13 at the upper end, which fits into a recess provided therefor in the arbor, thereby preventing the knife from dropping downwardly out of position. A bearing bushing 14 is provided in the upper end of each slot for supporting the knives against upward movement, these bushings having substantially semicylindrical bearing surfaces which engage the upper ends of the knives.

Each knife has a bit 15 thereon at the lower end which is adapted to cut through a pipe in response to movement of the lower end of the knife outwardly in swinging movement about the upper end as a pivot. To normally retain the lower ends of the knives within the slots out of cutting position, a straight spring member 16 is secured to the upper end of each knife and projects therefrom through an aperture 17 in the associated bushing 14 and into a recess 18 provided in the arbor 5. These recesses 18 are completely enclosed by the coupling member 3. The upper end of each of the spring members 16 rests against the arbor 5, thereby resiliently urging the lower ends of the knives inwardly.

Positioned immediately below the knives 12 and slidably mounted on the arbor 5 is an expander head 19 having a plurality of knife seats 20 there-

on and a plurality of recesses 21 therein. The recesses 21 are positioned between the knife seats 20 and alongside thereof for a purpose to be described later. The expander head 19 is provided 5 with a threaded shank 22 on the lower end thereof, which is adapted to be screwed into a connecting member 23. The connecting member 23 is slidable vertically on the arbor 5 but is capable only of limited rotary movement with respect 10 thereto. Thus the connecting member 23 is provided with splines 24 (Fig. 5) which normally engage against splines 25 on the arbor so that in response to counterclockwise rotation (with respect to Fig. 5) of the arbor 5 the connecting 15 member 23 and the expander head 19 are forced to rotate with the arbor. In this position, in which the splines 24 and 25 engage as shown in Fig. 5, the knife seats 20 on the expander head 19 are in alignment with the knives 12 so that in 20 response to downward movement of the arbor 5 and the knives with respect to the expander head 19, the lower ends of the knives 12 will ride down on the knife seats 20 thereby forcing the bits 15 outwardly into engagement with a pipe to be cut. 25 However, after the knives have been fully expanded to force the bits 15 completely through a pipe, it is desirable to be able to quickly retract the knives; and in accordance with the present invention this is done by permitting the arbor 5 30 and the knives 12 to rotate with respect to the expander head 19 in response to sufficient upward movement of the expander head 19 to fully expand the knives. This result is obtained by so positioning the upper ends of the splines 25 on 35 the arbor with respect to the lower ends of the splines 24 on the connecting member 23 that these splines disengage in response to a predetermined downward movement of the arbor with respect to the connecting member 23.

40 As previously mentioned, the head 19 is attached to the member 23 by the threaded shank 22. The cooperating threads on the shank and head are dimensioned to fit tightly so that the parts remain in whatever relative positions they 45 may be set. This makes possible the vertical adjustment of head 19 relative to member 23 to vary the extent to which the knives will have been opened at the time the splines 25 and 24 disengage.

50 Of course, in order to effect downward motion of the arbor 5 relative to the expander head 19 and connecting member 23, it is necessary to anchor the latter element against downward movement. To this end, there is positioned surrounding the arbor 5 below the connecting member 23 a spear head 26 which is freely rotatable on the arbor 5 and is provided with slip seats 27 on which are mounted pipe engaging slips 28. Downward movement of the connecting member 55 23 with respect to the spear head 26 is prevented by bearing rings 29 interposed therebetween and relative rotation between the spear head 26 and the connecting member 23 is impeded by friction shoes 30 which bear against the surface of an 60 annular groove in the connecting member 23 and are mounted on spring strip members 31 which are secured at their lower ends to the spear heads 26 as by screws 32. The slip seats 27 are inclined upwardly and outwardly so that when the slips 65 28 are moved upwardly along the seats they are forced outwardly into engagement with the pipe 1, thereby firmly locking the spear head 26 against either downward or rotary movement with respect to the pipe. It will be obvious that 70 75 when the spear head 26 is anchored to the pipe,

the previously mentioned knife expanding movement of the arbor 5 with respect to the expander head 19 may be obtained by merely lowering the arbor on the drill pipe 2.

However, before the spear head 26 can be anchored the slips 28 must be moved upwardly along their seats and to this end each slip 28 is connected by a slip rein 33 to a housing member 34 which is slidably mounted upon the lower arbor 7. The upper ends of the reins 33 are connected to their associated slips by bending the upper ends of the reins outwardly into recesses 35 provided therefor in the rear faces of the slips. The lower ends of the reins 33 are rigidly secured to the housing 34 by screws 36.

To normally retain the slips in retracted position (as shown in Fig. 2) the lower arbor 7 is provided with downwardly deflected ratchet threads 37 within the housing 34 and several split nut sections 38 having ratchet threads 20 adapted to cooperate with the threads 37 are mounted in pockets 38a in the housing 34. Each pocket 38a has sufficient depth radially to permit movement of the split nut section therein completely out of engagement with the ratchet threads 37 but is constantly urged inwardly toward the threads 37 by a straight spring member 39, the upper ends of these various spring members 39 being rigidly secured to the housing by bolts 40. The tension of the spring members 39 urges the split nut sections 38 inwardly toward the lower arbor 7 but permits the nuts to move outwardly and slip past the threads on the arbor in response to upward movement of the arbor. The lower face 34b of each pocket 38 is 35 inclined inwardly and downwardly at an angle of 30° and the lower face of each nut section is similarly inclined. The inclined bottom faces on the nut sections and the inclined bottom walls on the recesses cooperate to insure positive engagement of the ratchet threads on the nuts with the ratchet threads on the arbor to prevent downward movement of the arbor with respect to the housing while permitting disengagement of the threads in response to upward movement of the arbor with respect to the housing.

To impart upward force to the housing 34 to set the slips 28, the housing 34 is connected by a helical spring 41 surrounding the lower arbor 7 to a sleeve 42 which is slidably mounted on the arbor 7 therebelow. Sleeve 42 is provided with pipe engaging bow springs 43, these springs being rigidly attached to the sleeve 42 at their lower ends but having their upper ends free to permit radial expansion and contraction of the center portions of the bow springs. The bow springs 43 are provided with notches 44 thereon to increase the resistance of entry of the springs into the upper end of a pipe.

For a purpose to be described, later, the arbor 7 is reduced in diameter adjacent its lower end to provide a shoulder 45 and the sleeve 42 has mounted thereon intermediate the springs 43 a plurality of springs 46 which are anchored to the sleeve 42 at their upper ends by screws 47. These springs 46 are relatively short, being only about half the length of the springs 43, and have their lower ends inturned and fitted into recesses or openings 48 in sleeve 42. The lower wall of each recess 48 is extended outwardly to form an outwardly and upwardly extending lip 49 which engages the lower end of the associated spring 46 and limits outward movement of the spring. The tension of each spring 46 normally maintains its lower end against the

lip 49, in which position the extreme inner end of the spring is clear of the shoulder 45.

The device is operated as follows: Assuming that the cutter is secured to the lower end of a 5 drill string 2, it is first lowered into the well with all of the parts shown in the positions indicated in Figs. 1, 2 and 3. It will be observed that the split nut sections 38 are engaging the threads of the screws 37 on arbor 7 adjacent the lower 10 end of the latter, thereby maintaining the housing 34, reins 33 and slips 28 in lowermost position in which the slips are retracted so that they do not project beyond the outer periphery of the spear head 26. Furthermore, the slips 28 15 engage against the lower end of the spear body 27 holding the latter in lower position and the spear body in turn acting through the springs 34, the friction elements 30 and the connecting member 23 hold the expander head 19 in lower 20 position in which the knife seats 20 on the expander head are below the knives 12, under which conditions the knives are fully retracted.

As the device is lowered into the well, it will finally reach and enter the upper end of the 25 pipe to be cut, being guided into the pipe by the guide member 8 on the lower end of the arbor 7. The guide member 8 is dimensioned to enter freely within the pipe to be cut but the bow springs 43 project outwardly substantially 30 beyond the edge of the pipe so that they catch on the upper edge of the pipe and the notched portions 44 bind on the edge of the pipe and set up considerable opposition to the entry of the springs into the pipe. This informs 35 the operator at the surface that the pipe has been reached. Having this information, the operator then forces the tool into the pipe by applying more weight to it and continues to lower the tool until the point is reached at which 40 it is desired to sever the pipe. During this downward movement of the tool through the pipe the bow springs 43 are expanded tightly against the inside surface of the pipe and offer substantial frictional resistance to downward movement, 45 thereby compressing the coil spring 41 to a substantial degree. It will be observed that at this stage the compression of the spring 41 is produced without producing any upward movement of the housing 34 because the split nut 50 sections 38 are engaging the threads 37 on arbor 7. However, as a result of the frictional resistance of the bows 43 upon initial entry of the springs into the upper end of the pipe, the sleeve 42 is forced upwardly along the arbor carrying 55 the lower ends of the springs 46 above the shoulder 45 so that although, upon entry of the springs 46 into the pipe, they are bent inwardly the lower ends of these springs 46 cannot prevent upward movement of the housing 42 with respect to the arbor because of the fact that the 60 ends of the springs 46 are above the shoulder 45 resting against the smooth portion of the arbor 7 thereabove.

When the operator has lowered the tool to 65 the point in the pipe where he wishes to sever the latter, he stops downward motion of the drill string but does not retract the drill string. Therefore, the tool is stopped with the spring 41 compressed. The operator then rotates the drill 70 string to the right. This rotates the arbors 5 and 7 and the rotation of the threaded portion 37 of arbor 7 with respect to the split nut sections 38 (the latter being restrained from rotation by its connection through spring 41 to the 75 sleeve 42) permits the nut sections 38 and the

housing 34 to be slowly moved upwardly along the arbor 7 by the spring 41, thereby carrying the slips 28 upwardly along their seats 27 on the spear head into engagement with the pipe. If this motion is not sufficient to disengage the 5 nuts 38 from the threads 37 the continued rotation of the arbors merely causes the split nut sections 38 to slip over the ratchet threads 37. Rotation of the drill string is preferably continued until the spring 41 is fully expanded, 10 which usually results in the nuts 38 being completely released from the threaded section 37 of the arbor, after which the drill string is lowered to force the knives 12 downwardly onto the knife seats 20 on the expander head 19 to expand the 15 knives against the casing. During all this time the string maybe rotated and by applying sufficient weight to the arbors 5 and 7 the knives will be gradually forced outwardly by the knife seats 20 to force the bits 15 into and finally 20 through the pipe, severing the latter. During this stage of the operation the expander head 19 rotates with the arbor 5 and the knives 12 by virtue of the fact that the splines 25 on the arbor are in engagement with the splines 24 in 25 the connecting member 23 on which the expander head 19 is mounted. However, when the expander head 19 has been moved upwardly a sufficient distance to fully expand the knives 15, the splines 24 and 25 disengage as hereinbefore described, whereupon the rotation of the connecting member 23 and expander head 19 ceases by virtue of the fact that these members are restrained from rotation by the friction shoes 30. Therefore the arbor and the knives 12 rotate with 30 respect to the expander head 19 until the lower ends of the knives 12 ride off of the knife seats 20 into the recesses 21, whereupon the springs 16 immediately retract the knives.

Following completion of a cut in the manner described, the tool may be withdrawn from the well or it may be left in the well during subsequent operations. Thus, for instance, a pipe puller may be mounted on the same string with the pipe cutter to engage and remove the severed portion 40 of the pipe after the cutting operation has been completed in the manner described. In such instances it is often desirable to lock the cutter against subsequent operation so that it can be moved upwardly or downwardly at random 45 through the pipe without setting the slips. The present cutter may be locked against further operation by merely withdrawing the tool upwardly a short distance through the pipe after completion of the operations described. This upward movement immediately disengages the slips 28 from the pipe and permits them to fall into retracted position as shown in Fig. 2. During this operation the split nut sections 38 slip down over the ratchet threads on the screw 37 on arbor 7 50 and by virtue of the frictional resistance of the spring bows 43 against the pipe the sleeve 42 is retracted into full lowermost position on the arbor 7, in which position the shoulder 45 is positioned above the lower ends of the springs 46 and 55 the latter are forced inwardly by the pipe to engage against the shoulder 45 and prevent any upward movement of the sleeve 42 on the arbor 7 in response to subsequent downward movement of the arbor 7. Therefore, following the completion 60 of a cut as described and the upward movement of the tool through the pipe for a short distance, the sleeve 42 is positively locked in lowermost position as long as the tool remains within the pipe so that the tool can be raised or lowered or 65 70 75

rotated to any desired extent without any possibility of again setting the slips and actuating the cutting mechanism. However, if it is desired to produce another cut, the cutter may be immediately restored to its original normal position by withdrawing it from the pipe and again lowering it into the pipe. Upon withdrawal of the tool from the pipe the springs 46 are released so that their lower ends move outwardly, thereby disengaging the shoulder 45 on the arbor 7. This places the entire tool in the closed position shown in Figs. 2 and 3 and by then again lowering the tool into the pipe the operation described may be repeated to make another cut.

To simplify the explanation of the invention, it has been explained by describing in detail a particular form of cutter. Obviously many variations may be made in the particular construction described while still employing features of the invention. The invention is therefore to be limited only as to the extent set forth and defined in the appended claims.

I claim:

1. An inside pipe cutter comprising a cutter head adapted to be secured to a drill pipe, a cutter mounted on said head for movement outwardly into active position and inwardly into retracted or inactive position, means normally tending to move said cutter into inactive position, cutter-actuating means including anchoring means associated with said head for moving said cutter into active position in response to downward movement of said head with respect to said cutter-actuating means, and means responsive to upward movement of the device through a pipe for locking the head against subsequent downward movement with respect to said cutter-actuating means while the device remains within said pipe.

2. A casing cutter comprising an arbor adapted to be secured to the lower end of a drill pipe, a spear head slidably on said arbor, an expansible knife on said arbor, means for expanding said knife in response to downward movement of said arbor with respect to said spear head, slips on said spear head mounted for upward and outward movement thereon into pipe engaging position, a sleeve slidably mounted on said arbor below said spear head, means connecting said sleeve to said slips, a shoulder on said arbor, and spring latch means on said sleeve adapted to normally lie out of engagement with said shoulder, said spring latch means being so positioned as to contact and be deformed by a pipe when the device is inserted in said pipe whereby it engages said shoulder on said arbor to prevent downward movement of the arbor with respect to the sleeve, and bow springs on said sleeve for frictionally engaging a pipe and tending to carry the sleeve upwardly on the arbor when the latter is lowered through the pipe.

3. A device as described in claim 2 in which said means for connecting said sleeve to said slips includes a connecting member positively connected to said slips and yieldably connected to said sleeve, with means for releasably locking said connecting member against upward movement relative to said arbor, said yieldable connection between said connecting member and sleeve permitting sufficient upward movement of said sleeve with respect to said arbor and connecting member to carry said shoulder on the arbor below said spring latch means during downward entry of said sleeve into a pipe and maintain the shoulder below said latch means during sub-

sequent downward movement of the sleeve into the pipe.

4. A casing cutter comprising an arbor adapted to be secured to the lower end of a drill pipe, anchor means on said arbor adapted to be anchored within a casing or pipe, a cutter head on said arbor containing a vertical slot for a cutter, a cylindrical upper bearing member having an aperture extending therethrough in the upper end of said slot, a cutter bar mounted in said slot having a cylindrical upper end adapted to bear against said bearing member, a spring bar secured to and extending from the upper end of said cutter bar through said aperture in said bearing member, said arbor having a recess therein into which said spring bar projects, the upper end of the bar engaging the arbor to urge the lower end of the knife bar inwardly into said slot, and knife expander means comprising a wedge member connected to said anchoring means, said wedge member and anchoring means being slidable on said arbor whereby downward movement of the arbor and cutter head with respect to the anchor means forces the lower end of the knife outwardly from the arbor.

5. A casing cutter comprising an arbor adapted to be secured to the lower end of a drill pipe, an expander head slidably mounted on said arbor, anchor means for anchoring said expander head within a pipe against downward movement with respect to the pipe while permitting rotation of said head, a knife on said arbor above said expander head, said knife being pivotally secured adjacent its upper end to said arbor, said expander head having an inclined knife seat thereon adapted to force the lower end of said knife outwardly in response to downward movement of the arbor and knife with respect to said expander head, said expander head having a recess therein spaced circumferentially from said knife seat for permitting collapse of said knife in response to rotation of said arbor and knife with respect to said expander head, cooperating splines on said expander head and arbor, respectively, for normally preventing rotation of said arbor relative to said head, said splines being so positioned relative to each other as to disengage when said expander head reaches a predetermined position relative to said knife to permit rotation of said knife off said seat and into said recess, thereby automatically retracting the knife.

6. A casing cutter comprising an arbor adapted to be secured to the lower end of a drill pipe, an expander head slidably mounted on said arbor, anchor means for anchoring said expander head within a pipe against downward movement with respect to the pipe while permitting rotation of said head, a knife on said arbor above said expander head, said knife being pivotally secured adjacent its upper end to said arbor, and said expander head having an inclined knife seat thereon adapted to force said knife outwardly in response to downward movement of said arbor and knife with respect to said expander head, means for releasing said knife from said knife-seat in response to predetermined downward movement of said arbor with respect to said anchor means, said expander head having a threaded extension on the lower end thereof adapted to screw into cooperating threads on said anchor means whereby the vertical position of the expander head with respect to the anchor means may be adjusted by turning the expander head, to vary the range of movement of said knife.

7. A casing cutter comprising an arbor adapted to be secured to the lower end of a drill pipe, anchor means slidably mounted on said arbor for engaging a pipe, a knife on said arbor above said anchor means, an expander head positioned below said knife and having an inclined knife seat thereon adapted to force said knife outwardly in response to downward movement of said arbor and knife with respect to said head, means for releasing said knife from said knife-seat in response to predetermined downward movement of said arbor with respect to said anchor means, and extensible means connecting said head to said anchor for varying the range of movement of said knife. 5
8. A device as described in claim 5 with frictional means for frictionally interengaging said anchor means and expander head for frictionally resisting rotation of said expander head with respect to said anchor means. 10
9. A casing cutter comprising an arbor adapted to be secured to the lower end of a drill pipe, a spear head slidable on said arbor, an expandable knife on said arbor, means for expanding said knife in response to downward movement of said arbor with respect to said spear head, slips on said spear head mounted for upward and outward movement thereon into pipe-engaging position, a sleeve slidably mounted on said arbor below said spear head, means connecting said sleeve to said slips, friction means associated with said sleeve for frictionally engaging a pipe within which said device is positioned, said arbor having downwardly directed ratchet screw threads thereon, a split nut attached to said sleeve having upwardly directed ratchet threads thereon adapted to engage said threads on said arbor, and spring means for urging the nut sections into contact with the arbor thread whereby the arbor is free to move upwardly with respect to the split nut and sleeve and is normally prevented from downward movement with respect to the sleeve except in response to rotation of the arbor in one direction with respect to the sleeve. 15
10. A device as described in claim 9, in which said sleeve includes a housing for enclosing the sections of said split nut and said spring means comprises spring members extending vertically from said nut sections to said housing and attached thereto at their upper ends for supporting said nut sections with respect to the housing. 20
11. A casing cutter comprising an arbor adapted to be secured to the lower end of a drill pipe, 25
- a spear head slidable on said arbor, an expandable knife on said arbor, means for expanding said knife in response to downward movement of said arbor with respect to said spear head, slips on said spear head mounted for upward and outward movement thereon into pipe-engaging position, a sleeve slidably mounted on said arbor below said spear head, means connecting said sleeve to said slips, friction means associated with said sleeve for frictionally engaging a pipe within which said device is positioned, said arbor having screw threads thereon, a cooperating nut attached to said sleeve adapted to engage said screw threads on said arbor for normally preventing downward movement of the arbor with respect to the sleeve while permitting downward movement in response to rotation of the arbor in one direction with respect to the sleeve, in which a spring connection is provided for attaching said friction means to said sleeve, said spring connection being compressible in response to downward movement of said arbor through a pipe to exert a continued upward force on said nut and sleeves during subsequent rotation of said arbor while maintaining the arbor at a fixed level. 30
12. A casing cutter comprising an arbor adapted to be secured to the lower end of a drill pipe, a knife supported on said arbor for outward swinging movement, an expander head below said knife having an inclined knife-seat thereon for forcing said knife outwardly in response to downward movement of the arbor and knife with respect to the expander head, said head having a recess therein circumferentially spaced from said knife-seat for permitting collapse of said knife in response to rotation of the arbor and knife with respect to the expander head, anchor means rotatable on said arbor, a head-supporting member coupled to said anchor means for vertical movement therewith and rotary movement with respect thereto, cooperating means on said head-supporting member and arbor, respectively, for normally preventing rotation of said arbor relative to said member while permitting such relative rotation in response to predetermined downward movement of said arbor relative to said member, and means for vertically adjustably connecting said head to said member for movement therewith whereby the range of outward movement of said knife prior to collapse of the knife may be varied. 35
